(57) **CLAIM**

The ornamental design for a cooking device, as shown and described.

DESCRIPTION

FIG. 1 is a front perspective view of a cooking device of the present invention showing our new design;

FIG. 2 is a front side elevation view thereof;

FIG. 3 is back side elevation view thereof;

FIG. 4 is a side elevation view thereof;

FIG. 5 is another side elevation view thereof

FIG. 6 is a top plan view thereof; and,

FIG. 7 is a bottom plan view thereof.

In the drawings, the broken lines illustrate portions of the cooking device and form no part of the claimed design.
